(57) **CLAIM**

The ornamental design of a vacuum cleaner nozzle assembly, as shown and described.

DESCRIPTION

FIG. 1 is a perspective view of a vacuum cleaner nozzle assembly showing our new design;
FIG. 2 is a left side elevational view thereof;
FIG. 3 is a front elevational view thereof;
FIG. 4 is a right side elevational view thereof;
FIG. 5 is a rear elevational view thereof; and,
FIG. 6 is a top plan view thereof.

The details shown in broken lines in FIGS. 1-6 are for illustrative purposes only and form no part of the claimed design.
